TWO-FEED KNITTING MACHINE

Howard Grady Dickens, Thomasville, N. C., assignor to Scott & Williams, Incorporated, New York, N. Y., a corporation of Massachusetts

Application November 26, 1932, Serial No. 644,525

11 Claims. (Cl. 66—24)

This invention relates to knitting machines and more particularly to circular knitting machines known as two-feed machines and arranged to knit two courses upon each revolution when both yarn feeds are in use and it is an object of this invention to provide an improved knitting machine of the type described. It is also an object of this invention to provide in a circular knitting machine arranged for rib and plain knitting and welt transfer, an auxiliary yarn feed so positioned and arranged as to permit the machine to operate in a satisfactory manner as a two-feed machine during plain knitting.

In the drawings

Fig. 1 is a view in elevation of the head of a knitting machine constructed in accordance with this invention, parts being broken away to show other parts more clearly;

Fig. 2 is a section taken on line 2—2 of Fig. 1 and showing the operating cams for the cylinder needles in plan view;

Fig. 3 is a fragmentary view in elevation of the knitting machine head shown in Fig. 1 and showing the means for supplying the auxiliary yarn at the auxiliary knitting point;

Fig. 4 is a fragmentary view in elevation of the yarn guide shown in Fig. 3 looking from the right in Fig. 3;

Fig. 5 is a fragmentary plan view of the needle dial and sinker ring showing the operating means for the auxiliary cam for withdrawing the sinkers;

Fig. 6 is a partial horizontal section of the sinker cam ring showing the auxiliary sinker operating cams at the auxiliary knitting point and the relation of the auxiliary sinker operating cams to the main sinker operating cams;

Fig. 7 is a fragmentary view in elevation showing part of the operating means for the auxiliary knitting and sinker cams and the movable main knitting cam;

Fig. 8 is a fragmentary view in elevation looking in a direction opposite to that of Fig. 7 and showing the operating cams for the auxiliary knitting and sinker cams;

Fig. 9 is a view in elevation looking from the right in Fig. 8;

Figs. 10, 11 and 12 are diagrammatic views showing the cylinder needle operating cams developed in the plane of the paper, Fig. 10 showing the operation of the cylinder needles during the knitting of the heel and toe; Fig. 11 during the knitting of rib fabric and Fig. 12 during the knitting of plain fabric, as in the leg, as a two-feed machine;

Fig. 13 is a view in elevation of a stocking knit by a machine constructed in accordance with this invention; and

Fig. 14 is a view drawn to an enlarged scale of a portion of the fabric of the leg of the stocking shown in Fig. 13.

In the drawings the invention is shown in connection with a well-known type of Scott & Williams circular knitting machine arranged for both plain and rib knitting and for automatically turning the welt such as is shown in the patent to Scott, No. 1,641,101, issued August 30, 1927. The machine is arranged for two feeds and adapted to tuck at the main feed. As shown, the machine comprises the needle cylinder 260 with its needles and the needle operating cams, the dial D with its needles, sinker ring 300 with its sinker operating cams, latch guard ring 550, yarn guides F' associated and operated as shown in Patent No. 1,641,101.

Previously, in machines for knitting rib fabrics or automatically turned welts, the auxiliary yarn feed has been placed to the left of the usual left hand stitch cam 360 as shown in Fig. 11 and this placement leaves no room for needle selection between the main and auxiliary yarn feeds and rendered patterning in the auxiliary yarns difficult, if not impossible. Where a pattern is formed by means of tuck stitches taken at the main yarn feed, the pattern is broken on the instep on the first revolution of round-and-round knitting after coming off the heel. In order to overcome the objections arising from placing the auxiliary or additional yarn feed at the left the additional or auxiliary yarn feed is placed at the most desirable point at the right of the right hand stitch cam 361 and the transfer cam 25 of Patent 1,641,101 which raises the jackless needles for taking the loops from the dial after rib knitting is modified in length and height without impairing its operation, to permit of the insertion of cams 30 and 31. These cams cooperate with the needle butts to form a knitting wave, cam 30 raising all the needles to clear their latches and take the auxiliary yarn and cam 31 lowering the needles to cast off the loops previously taken. Co-operating in the knitting at this point are auxiliary cams in the sinker ring 300 comprising a cam 32 to withdraw the sinkers and a cam 33 to reinsert or restore the sinkers to their forward position.

Cams 30 and 31, as shown in Figs. 10, 11 and 12 would, if left in their operative or active positions, prevent the usual operation of cam 25 in transferring loops from the dial to the jackless 110

needles, so cams 30 and 31 are arranged to be withdrawn from their active positions when not in use and to be inserted when the machine is to be operated as a two-feed machine and the auxiliary yarn feed F^2 is inserted. To provide for the insertion and withdrawal of the cams 30 and 31 the cams are slidably mounted in brackets 34 and 35, respectively, carried by the bed plate B and are biased by springs within the brackets toward positions in which the cams do not engage the needles. To operate the cams there is provided a shaft 36 journaled in bearing brackets 37 carried by the bed plate B and having crank arms 38 secured thereon and provided with adjustable contacts 40a and 41a arranged to engage the outer ends of the cams 30 and 31 respectively. One end of the shaft 36 is bent to form a crank 36a having a loop or eye 36b at the free end thereof. Extending through the eye 36b is a rod or link 39 having an adjustable collar 39' secured to its upper end portion and having its lower end connected to one end of a lever 40b, the other end of which is pivotally connected at 41b to the machine frame. Adjustably mounted in the lever 40b is a contact member 42 which engages with cams 43 and 44 carried by a cam plate 45 secured to a shaft 46 journaled in bearings carried by the frame. Also mounted upon the shaft 46 are the usual pattern chain sprocket and its operating ratchet (not shown) which operates the pattern chain to control the operation of the shaft 46 in the usual manner, such as is shown in the patent to Scott, No. 1,152,850, September 7, 1915. The connections between the lever 40b and the needle operating cams 30 and 31 are such that when either cam 43 or 44 presses the lever 40 down the needle operating cams 30 and 31 are moved inwardly to engage the needle butts.

Also fixed upon the shaft 36 is a crank arm 48 which extends upwardly from the shaft 36 to a point above the sinker ring 300 and is provided with an inwardly projecting arm in which is mounted a plunger 49 pressed downwardly by a spring 50 and positioned to engage and press downwardly a lateral extension 51 of a lever 52 pivoted at 53 on the sinker ring 300 when the arm 48 is moved inwardly by the shaft 36. Secured to the lever 52 is the auxiliary sinker withdrawing cam 32 which is moved into operative or active position when the lever 52 is pressed downwardly. A spring 54 engaging the plunger 55 and a housing 56 formed integral with the lever 52 tends to hold lever 52 and cam 32 in the raised or inactive position. Secured to the arm 48 is a laterally projecting arm 48a having an opening therein in which is guided one end of a link or wire 57 the other end of which is pivotally connected to the pivotally mounted reinserting cam 33. A spring 58 confined between the arm 48a and the cam 33 and surrounding the link 57 serves to force the cam 33 inwardly with a yielding pressure when the arm 48 is moved inwardly by the shaft 36. A stop 60 on the link 57 limits the expansion of spring 58 and insures the withdrawal of cam 33 as the cam 48 is moved outwardly. An arm 61 secured to the shaft 36 engages the machine bed plate and limits the movement of the shaft 36 in one direction.

To the bracket A which supports the dial spindle d and the gearing for driving it, there is attached a bracket 63 having spaced ears 64 in which a bell crank 65 is pivotally supported and a laterally extending arm 66 carrying guides 67 in which the auxiliary yarn guide F^2 is slidably mounted. At its upper end the yarn guide

F^2 is engaged by one arm of the bell crank 65 and a spring 68 connected to the upper end of the yarn guide F^2 and to one of the guides 67 tends to move the yarn guide F^2 downwardly to its active or feeding position. To the other arm of the bell crank 65 there is pivotally secured a pin 70 having an opening therein through which extends one end of a link or wire 71, the opposite end of which is pivotally secured to an extension 72 of one of the usual yarn guides F^1 in the throat plate F. An adjustable collar 73 secured to the wire 71 adjacent the pin 70 insures the operation of the bell crank 65 in a direction to raise the yarn guide F^2 . The yarn guide F^1 to which the link 71 is connected is operated from cams on the main drum by means of a push rod 460 in the usual manner and the connection to the yarn guide F^2 is such that the yarn guide F^2 is operated to its active or feeding position by a movement of the yarn guide F^1 to which it is connected to the active or feeding position although in this construction this particular yarn guide F^1 is not used to feed yarn directly.

In the arrangement shown in the drawings occasional long latch needles n' as shown in Fig. 11 are placed on the needle cylinder with the usual short latch needles n^2 and the right hand stitch cam 361 is pivoted so that it may be positioned in a lower position, as shown in dotted lines in Fig. 12, in which it raises the short latch needles far enough to clear their latches but does not clear the latches of the long latch needles or in an upper position, as shown in solid lines in Fig. 12, in which the latches of all needles are cleared. To operate the cam 361, the cam is connected by a link 75 to one end of a lever 76 which is centrally pivoted at 77 on the post or support 401 and has its opposite end positioned to be engaged by one end of a lever 78. A spring 77a connected to the lever 76 and the base plate B tends to shift the cam 361 to its lower position. The lever 78 is centrally pivoted at 79 on the machine frame and has at its opposite end an adjustable contact 80 positioned to be engaged by one end of a lever 81. Adjacent the contact 80 the lever 78 is provided with a finger 82 arranged to be engaged by a cam 83 on the gear wheel 84 when the lever 81 is operated to permit the lever 78 to be moved to the left in Fig. 7. The lever 81 is centrally pivoted on the machine frame at 85 and has its opposite end positioned to be engaged by cams 86 and 87 on the belt shipper drum 88 secured to shaft 46 and operated with the cam disk 45. The arrangement is such that while cam 86 or 87 engages lever 81, the lever 81 holds the lever 78 in a position in which the finger 82 is not engaged by the cam 83 and the lever 78 engages lever 76 and causes lever 76 to hold cam 361 in its upper or raised position. When the cams 86 and 87 are moved from beneath the lever 81, the lever 81 permits the lever 78 to move so as to place the finger 82 in a position to be engaged by the cam 83 at each revolution of the gear 84. Finger 82 when engaged by the cam 83 is forced outwardly and shifts the lever 78 to operate lever 76 to raise the cam 361 to its upper position and when cam 83 moves from engagement with the finger 82 the levers 78 and 76 are operated to place the cam 361 in its lower position. The gear 84 is driven from the main drive shaft 90 by means of a gear 91 and the gear ratio is such that gear 84 revolves once for each four revolutions of the needle cylinder.

Cam 83, as shown, is arranged to engage finger 82 through an arc of substantially 90° so that the cam 361 will be in its lower position throughout three complete revolutions and in its upper position during one revolution of the needle cylinder.

In the knitting of a stocking the auxiliary needle cams 30 and 31, the auxiliary yarn feed F² and the auxiliary sinker cams 32 and 33 will be withdrawn or held in inactive position as shown in Fig. 11 during the starting of the stocking and the knitting of the welt and ribbed top T and the operations will be as set forth in Patent No. 1,641,101, the cylinder needles N and their jacks 380 cooperating during the knitting of the ribbed top T with the jack raising cam 366, transfer cam 25, dividing cam 4, stitch cams 361, 357 and 360 and lowering cam 8 to form the ribbed fabric and make the transfer as described in that patent. Upon the completion of the transfer and the raising of the dial the pattern chain is racked forward and the knitting of the stocking leg L begins. The same racking movement engages cam 44 with lever 40b causing link 38 to operate shaft 36 to shift the auxiliary knitting cams 30 and 31 and the auxiliary sinker operating cams 32 and 33 into operative or active positions. The same racking movement also shifts the cam 86 from beneath the lever 81 permitting the lever 81 to move away from the lever 78 and permitting the lever 78 to move inwardly and place finger 82 in position to be operated by the cam 83 thereby causing the right hand stitch cam 361 to alternately hold its lower position for three complete revolutions and its upper position for one. At the same time the main pattern drum is operated to withdraw the push rod 460 from the yarn guide F¹ which operates the auxiliary yarn guide F² permitting the yarn guide F² to be moved by spring 68 to yarn feeding position. With the auxiliary cams and yarn feed in operative position, all of the needles are raised by the raising cam 30, as shown in Fig. 12, to clear their latches and take the auxiliary yarn at the auxiliary yarn feed F² and the needles are then operated by the auxiliary knitting cam 31 to draw the new loops and cast off the previous loops which will in this case be loops of the yarn fed by the yarn guide F¹. During the taking and knitting of the yarn at the auxiliary yarn feed the auxiliary sinker cam 32 withdraws the sinkers to relieve the tension upon the loops and the cam 33 reinserts the sinkers upon the casting off of the previous loops. The needles are raised by the cam 40 and pass to the right hand stitch cam 361. This cam, as previously described, is alternately in a lower position for three revolutions and in an upper position for a single revolution of the needle cylinder. While in its lower position the cam 361 raises all needles to take the yarn from the main yarn guide F¹ at the throat F and raises the short latch needles far enough to clear their latches but does not raise the long latch needles far enough to clear their latches. When the cam 361 is in its raised position the needles take the yarn at the main yarn feed F¹ and all needles are raised far enough to clear their latches. The long latch needles, therefore, form tuck stitches in the auxiliary yarn during each of the three revolutions the cam 361 is in its lower position and cast off both loops at the auxiliary knitting cams; and cast off their loops at both the main and auxiliary knitting cams when the cam 361 is in its raised position during the fourth revolution. The short latch needles cast off their loops and

knit at both main and auxiliary knitting cams in every revolution. This operation provides, as shown in Fig. 14, a fabric having alternate courses of the main and auxiliary yarns and tuck stitches at every other course of courses 3 to 8 and then two courses, courses 1 and 2, without the tuck stitches. It also causes the main yarn to be cast to the back of the needles so that a vertical stripe of the auxiliary yarn is formed in the wale of each long latch needle. These stripes are interrupted at the courses 1 and 2, in which the long latch needles are caused to knit at the main knitting cams by the cam 361 being in raised position.

Upon the completion of the leg L to the heel h the cam dials 45 and 88 are again racked causing the cam 44 to be disengaged from the lever 40b and the cam 87 to engage the lever 81 withdrawing the auxiliary knitting cams 30 and 31 and sinker cams 32 and 33 and causing the knitting cam 361 to be held in its upper position. At the same time the push rod 460 controlling the auxiliary yarn feed F² is operated to withdraw the auxiliary yarn. The heel is then knit as described in Patent No. 1,641,101, the cylinder needles and cams cooperating as shown in Fig. 10. Upon the completion of the heel the cam disks 45 and 88 are again racked to cause cam 43 to operate lever 40b to place the auxiliary knitting and sinker cams in active positions and to cause cam 87 to pass from beneath the lever 81 and again permit the operation of cam 361 to its upper and lower position. The auxiliary yarn feed is also thrown in at this time and the operation continues during the knitting of the instep i and sole s.

When the long butt needles are raised by the switch cam 415 at the beginning of the heel the latches of all the needles raised are cleared, the regular length latches having a loop of the main yarn while the longer latches have loops of both main and auxiliary yarns, but as in this arrangement the latches of all needles are cleared at this point by the cam 30, the loops are in the normal relation to the instep needles when these needles are returned to operation by the switch cam 415 after the completion of the heel and are raised by the cam 30. When returned to operation it will be noted the needles are not lowered far enough to have the loops close the latches so the needles engage the auxiliary yarn when raised by the cam 30.

If the auxiliary yarn feed were placed at the left of the stitch cam 360 in Fig. 12, the long latch needles would not be cleared in two-feed tuck knitting when they were raised to take the main yarn and would be cleared of both main and auxiliary yarns when raised to take the auxiliary yarn. In going onto the heel the long latch needles would have their latches cleared when the needles were raised by the switch cam 415 and 135 these needles consequently would not have the loops of auxiliary yarns in their hooks when drawn down to take the main yarn. The loops of the auxiliary yarn would accordingly be cast off when these needles were lowered by the stitch 140 cam 360 and the tucking would be interrupted on the instep during the first revolution of round-and-round knitting after coming off the heel.

Upon the completion of the instep and sole the cam disks 45 and 88 are again racked to disengage the cam 43 from the lever 40b and to engage the cam 86 with the lever 81, withdrawing the auxiliary cams and holding the cam 361 in its upper position. The auxiliary yarn guide F² is also withdrawn at this time. The knitting of 150

the toe *t* is thereupon carried out and the stocking finished in the manner described in Patent No. 1,641,101. While this invention has been shown and described in connection with a particular rib knitting machine, it will be apparent that the invention is not limited to the particular application shown as it may be used with machines of other design.

What is claimed is:—

- 10 1. In a circular knitting machine arranged for rib and plain knitting and having cams forming the usual knitting wave, a cam for transferring loops from the dial needles to the cylinder needles and means for forming tuck stitches on some 15 of the needles at the main knitting wave, cams for forming an auxiliary knitting wave in the region of said transfer cam during plain knitting and means for rendering said cams forming the auxiliary knitting wave active and inactive.
- 20 2. In a circular knitting machine arranged for rib and plain knitting and having cams operating needles to form the usual knitting wave, sinker operating cams, a cam for transferring loops from the dial needles to the cylinder needles 25 and means for forming tuck stitches on some of the needles at the main knitting wave, auxiliary cams for forming an auxiliary knitting wave in the region of said transfer cam during plain knitting, auxiliary sinker operating cams 30 operating the sinkers at the auxiliary knitting wave and means for rendering said auxiliary cams active and inactive.
3. In a circular knitting machine arranged for rib and plain knitting and having cams operating needles to form the usual knitting wave, a cam for transferring loops from the dial needles to the cylinder needles and means for forming tuck stitches on some of the needles at the main knitting wave, auxiliary cams for forming an 40 auxiliary knitting wave at said transfer cam during plain knitting, an auxiliary yarn guide to feed yarn to the needles at the auxiliary knitting wave and means to render said auxiliary cams and yarn guide active and inactive.
- 45 4. In a circular knitting machine arranged for rib and plain knitting and having cams operating needles to form the usual knitting wave, a cam for transferring loops from the dial needles to the cylinder needles and means for forming tuck stitches on some of the needles at the main knitting wave, movable auxiliary cams for forming an auxiliary knitting wave during plain knitting and means to shift said auxiliary cams to an active position at said transfer cam to form said 55 knitting wave.
5. In a circular knitting machine arranged for rib and plain knitting and having cams operating needles to form the usual knitting wave, a cam for transferring loops from the dial needles to the cylinder needles and means for forming tuck 60 stitches on some of the needles at the main knitting wave, auxiliary cams for forming an auxiliary knitting wave during plain knitting and means to insert said auxiliary knitting cams to form a 65 knitting wave over said transfer cam position.
6. In a circular knitting machine arranged for rib and plain knitting and having cams forming a main knitting wave, a transfer cam and needles with latches of different lengths, auxiliary cams for forming an auxiliary knitting wave at the transfer cam during plain knitting and clearing the latches of all needles, yarn feeds at said main and auxiliary knitting cams and means to cause said main knitting wave to clear the short latch needles only. 80
7. In a circular knitting machine arranged for rib and plain knitting and having cams forming a main knitting wave, a transfer cam and needles with latches of different lengths, auxiliary cams for forming an auxiliary knitting wave at the transfer cam during plain knitting and clearing the latches of all needles, yarn feeds at said main and auxiliary knitting cams and means to vary the main knitting wave to clear the latches of the short latch needles or the latches of all the 95 needles.
8. In a circular knitting machine arranged for rib and plain knitting and having cams operating needles in a main knitting wave during rotary and reciprocating knitting and a transfer cam, 100 cams operating needles in an auxiliary knitting wave at said transfer cam during rotary knitting and means operating one of the cams forming the main knitting wave to knit tuck work on some of the needles during rotary knitting. 105
9. In a circular knitting machine arranged for rib and plain knitting and having cams operating needles in a main knitting wave during rotary and reciprocating knitting and a transfer cam, 110 cams operating needles in an auxiliary knitting wave at said transfer cam during rotary knitting, means to shift the cams forming the auxiliary knitting wave to operative and inoperative positions and means operating one of the cams forming the main knitting wave to knit tuck work on 115 some of the needles during rotary knitting.
10. In a circular knitting machine arranged for rib and plain knitting and having cams operating needles in a main knitting wave during rotary and reciprocating knitting and a transfer cam, 120 cams operating needles in an auxiliary knitting wave over said transfer cam during rotary knitting, means to shift the cams forming the auxiliary knitting wave to operative and inoperative positions and means operating one of the cams 125 forming the main knitting wave to knit tuck work on some of the needles during rotary knitting.
11. In a circular knitting machine arranged for rib and plain knitting and having cams operating needles in a main knitting wave during rotary 130 and reciprocating knitting and a transfer cam, cams at the extremities of said transfer cam operating needles in an auxiliary knitting wave during rotary knitting, means to shift the cams forming the auxiliary knitting wave to operative and inoperative 135 positions and means operating one of the cams forming the main knitting wave to knit tuck work on some of the needles during rotary knitting.

HOWARD GRADY DICKENS. 140
